ADJUSTABLE PATTERN

John Bukovy, Akron, Ohio

Application August 26, 1938, Serial No. 226,934

4 Claims. (Cl. 33—14)

This invention relates to improvements in adjustable garment patterns.

Objects of the invention are to provide a pattern of simple, economical construction which is composed of separable sections which may be quickly and conveniently adjusted to cut parts of garments of different sizes.

Other objects are to provide improved means for securing said sections in assembled relation whereby sections differing in size and contour may be selectively employed and adjustably connected to form accurate templets for parts of garments of different types and styles.

The above objects are accomplished and additional ends are attained by the novel construction, combination and arrangement of parts hereinafter described with reference to the accompanying drawing in which there is shown an illustrative embodiment of the invention, it being understood that the invention is not confined to the exact structure illustrated and that changes and modifications may be made which come within the scope of the appended claims.

In the drawing:

25 Figure 1 is a plan view of a pattern constructed in accordance with this invention.

Figure 2 is a cross sectional view taken as indicated by the lines 2—2 of Figure 1 and showing the pattern in an expanded condition,

30 Figure 3 is a fragmentary, sectional view taken as indicated by the lines 3—3 of Figure 1.

Proceeding now to a detailed description of the invention with reference to the particular adaptation thereof disclosed in the drawing, the numerals 4, 5, 6, 7 and 8 are employed to denote sections which may be formed of any suitable sheet material and each of which is designed to form parts of a pattern.

In the drawing, the section 4, 5, 6, 7 and 8 have parallel, adjacent edges and form longitudinal parts of a pattern. Each of the sections 4, 5, 6, 7 and 8 are provided with a channel member 9 preferably composed of relatively thin, sheet metal having its edge portions 10 and 11

45 turned upwardly and inwardly to form a channel 12 of dove-tail cross section. The bottom wall 13 of the channel member 9 is preferably flat and is secured flat against one of said sections by the grommets 14 or any suitable means.

50 Each channel member extends transversely across the section on which it is mounted in alignment with like channel members which are likewise secured to the other sections.

In the particular form of the invention illustrated, each section is provided with two channel

members 9 which are secured thereto as above described and which extend thereacross in parallel, spaced relation.

The numeral 15 denotes a strip preferably composed of sheet metal having edge portions 16 and 17 which are inclined downwardly and outwardly to snugly fit in the channel 12 of channel member 9. It will be noted that the rivets or grommets 14 are positioned along the medial line of the bottom wall 13 with the edges 16 of the grommet spaced inwardly from the side walls 10 and 11 and that the strips 15 may be positioned in the channel members 15 without contact with the heads of the grommets 14.

In use, the sections 4, 5, 6, 7 and 8 are selected and assembled to provide a pattern of the desired contour with the channel members 9 arranged in straight parallel rows transversely across the pattern. The strip 15 is slid longitudinally into the channels 12 of the channel members 9 of each row so as to extend entirely across the pattern and slidably secure the sections on the strips 15. The strips 15 are ordinarily longer than the width of the pattern and project from one side thereof as shown in Figure 1. On one end portion of each strip 15 there is provided graduations 18 indicating sizes. With the sections 12 thus slidably secured to the strip 15 the section 8 may be slid outward to the desired marking 18 and the other sections slidably adjusted to properly space the same in the pattern thus forming a templet which can be used to cut parts of the garments of different sizes.

It will be seen that a number of sections each of a different contour may be employed and interchangeably used with one or more of the sections to form parts of garments of different types and styles.

It will thus be seen that this invention provides a pattern composed of separable sections with simple, efficient, adjustable means for securing said sections in assembled relation whereby the pattern may be quickly and conveniently expanded to provide a templet for parts of garments of different sizes and that sections may be interchangeably used to outline parts for garments of different types and styles.

The invention having been thus illustrated and described, what I claim as new and desire to secure by Letters Patent is:

1. A pattern composed of a plurality of sections, a channel member secured to each section and disposed transversely thereof and an elongated strip slidably received in the channels on

a plurality of sections for adjustably securing said sections in assembled relation.

2. A pattern composed of a plurality of flat sections, a plurality of channel members secured to each section in spaced, parallel relation, each channel member on each section extending transversely thereof in alinement with the like channel members on the other sections and strips slidably received in the alined channel members 10 for adjustably holding the sections in assembled relation.

3. In a pattern of the character described, a plurality of flat sections, two channel members secured to each section, said channel members 15 extending transversely across each section in spaced, parallel, relation and in alinement with

channels on the other sections, said channel members having channels of dove-tail cross section and a metal strip having downturned edge portions entered in said channels to hold said sections in assembled relation.

4. In a pattern of the character described, a plurality of sections, a plurality of strips extending across said sections and projecting beyond one lateral side of the pattern, channel members secured to said sections, said strips slidably received in said channel members to adjustably hold the sections in assembled relation and graduations on portions of said strips which project beyond the pattern said strips for designating sizes.

JOHN BUKOVY.
